SLINGSHOT

Frederic B. Hodge, Pleasant Ridge, Mich.

Application March 30, 1948, Serial No. 145,429

Term of patent 7 years

(Cl. D34—15)

To all whom it may concern:

Be it known that Frederic B. Hodge, a citizen of the United States of America, and a resident of Pleasant Ridge, in the county of Oakland and State of Michigan, has invented a certain new, original, and ornamental Design for Sling Shot, of which the following is a specification, reference being had to the accompanying drawing, forming a part thereof, and wherein:

Fig. 1 is a side elevational view of a sling shot, showing my new design;

Fig. 2 is a front elevational view thereof; and
Fig. 3 is a top plan view thereof.

The dominant features of my design reside in the parts shown in full lines.

I claim:

The ornamental design for a sling shot, substantially as shown and described.

FREDERIC B. HODGE.
